UNITED STATES PATENT OFFICE.

JOHN GEARY, OF PHILADELPHIA, PENNSYLVANIA, ASSIGNOR TO SHAW & GEARY, OF SAME PLACE.

DOOR-SPRING CONNECTION FOR ELECTRIC BURGLAR-ALARMS.

SPECIFICATION forming part of Letters Patent No. 398,144, dated February 19, 1889.

Application filed August 22, 1888. Serial No. 283,416. (No model.)

To all whom it may concern:

Be it known that I, JOHN GEARY, a citizen of the United States, residing at Philadelphia, in the county of Philadelphia and State of Pennsylvania, have invented certain new and useful Improvements in Door-Spring Connections for Electric Burglar-Alarms; and I do hereby declare the following to be a full, clear, and exact description of the invention, such

as will enable others skilled in the art to which it appertains to make and use the same.

My invention has relation to door-springs or connections for burglar-alarms, and has for its object the provision of a door-spring of comparatively simple and inexpensive construction, and in which the contacting surfaces which make and break the electric circuit as the door is opened and closed shall slide on one another, so as to keep them clean and maintain good contact.

My invention consists in the novel construction, combination, and arrangements of parts, hereinafter described and specifically claimed.

In the accompanying drawings, Figure 1 is a vertical sectional view of a portion of a door and a door-jamb with my improved connection in position in the jamb, the door being closed; Fig. 2, a similar view showing the door open, the connection being shown in side elevation in both views, and Fig. 3 a perspective view of the connection, and Fig. 4 a perspective view of a modification.

A designates the face-plate of the connection, which is let into the jamb so as to be flush with the surface of the same, and is held in position by screws.

a B B designate arms which project laterally from each edge of the plate A at or about the middle, and support a plate, C, which latter is formed with notches or holes that receive similarly-shaped lugs b b on the ends of arms B B.

D designates a block of insulating material, which is secured between the ends of arms B B and the plate C, and E a spring contact-piece, which is attached to the block D, turned in between the arms B B, and has its end e bent parallel to the plate A.

F designates a sliding plug which passes

through holes in the plates A C, and carries a metallic contact-piece, G, which makes contact with the spring contact-piece E when the door is open, and serves as a stop to limit the outward movement of the plug F.

55

H designates a spiral spring that surrounds the plug F between the plate C and the contact piece G, and serves to project the plug outwardly as the door is opened.

The operation of the above-described device is accomplished by the opening and closing of the door in the following manner: When the door is closed, the parts are in the position shown in Fig. 1, and the plug F having been forced in against the pressure 65 of spring H, the contact-piece G is held out of contact with spring contact-piece E. Upon opening the door the plug F is forced outwardly by the spring H, and the contact-piece G is brought into contact with the 70 spring contact-piece E, and the latter, being rigidly secured at one end to the insulating-block D, slides upon the contact-piece G as the plug is moving outwardly, thus serving to keep the contacting surfaces bright and clean. 75 Upon closing the door the plug is forced inwardly and the contact-pieces slide upon one another until such time as they part and the contact is thereupon broken.

It will be observed that the insulating-block is secured in position between the ends of arms B B and the plate C, being cut away to permit of the passage of the dovetail lugs b b. The plate C and the insulating-block are secured in position by riveting 80 or upsetting the ends of the lugs b b, and by this construction the parts are secured together firmly and without the use of screws, thus cheapening the cost of manufacture, while the parts are more securely held together than if screws were employed. The spring contact-piece G, being mainly between the arms B B, is protected from accidental injury when the device is being placed in position, and the entire device is neat, 90 compact, and not liable to get out of order or become inoperative.

Having described my invention, I claim—

In a door-spring connector for electric burglar-alarms, the combination of movable 100

plug F, contact-piece G, carried thereby, spring contact-piece E, plate C, through which the movable plug F works, and insulating-block D, with the supporting-arms B 5 B, having lugs b b, whereby the insulating-block D and plate C are supported, substantially as described.

In testimony whereof I have affixed my signature in presence of two witnesses.

JOHN GEARY.
